UNITED STATES PATENT OFFICE

GUSTAF E. JACOBSON, OF SOUTH ORANGE, NEW JERSEY

OIL BURNER

Application filed September 9, 1926. Serial No. 134,368.

This invention relates to oil burners, and while intended more particularly for use in connection with house-heating furnaces, it is to be understood the invention is not limited to such use.

The objects of the invention are to provide an oil burner which can be readily applied to boilers now in use; to provide a construction enabling the burner to be set in the usual ash-pit of the furnace; to obtain injection of the fuel oil and air by means of steam generated by the burner; to enable gravity feed for the fuel oil to be employed; to obtain a thorough mixture of the fuel oil and air; to provide an auxiliary supply of air; to obtain a single control for regulation of the flame; to enable the parts to be readily assembled and broken parts replaced; to secure simplicity of construction and operation, and to obtain other advantages and results as may be brought out in the following description.

Referring to the accompanying drawings, in which like characters of reference indicate the same parts throughout the several views,

Figure 1 is a vertical central sectional view through an oil burner embodying my invention;

Figure 2 is a horizontal sectional view on line 2-2 of Fig. 1, and

Figure 3 is a sectional view on another horizontal plane as indicated by line 3-3 of Fig. 1.

In the specific embodiment of the invention illustrated in said drawings, the reference numeral 1 indicates an injecting chamber or fitting having a steam nozzle 2 entering from the bottom and a fuel nozzle 3 entering diagonally upward so its jet opening will be adjacent the jet opening of the steam nozzle, said chamber also having an air inlet 4 through which the mixture passes from said chamber. At the upper end of said tube 5 is a hood 6 forming a mixture chamber 7 from which the combustible mix-

tube 5 is preferably shaped as a Venturi tube, screw threaded on its outside at opposite ends so that it may screw into fitting 1 at one end and receive a correspondingly threaded portion of the central hub 81 of the shelf 8 at its other end. It may be noted that said shelf depends cylindrically outside of the tube 5 for a distance, as at 82, and then flares outwardly forming the shelf proper 8. The hood 6 has its closed top portion spaced a distance above the upper end of the tube 5 and shelf hub 81 and depends downwardly out side of the cylindrical part 82 of the shelf with an annular space therebetween and a restricted feed gap 9 at the bottom of the

Below the lower annular edge of the shelf 8 is a drip pan 10 which by preference is a part of the same casting with the shelf shown connected by vanes 11 so as to provide an auxiliary air supply gap 12. By virtue of this auxiliary air supply gap, such fuel as passes to the bottom of the shelf for want of oxygen becomes ignited as it passes to the drip pan 10. Preferably the connecting vanes 11 between the shelf and drip pan are diagonal with respect to radial lines so as to give the entering air a whirling action which will cause it to mix more thoroughly with the fuel.

The outer margin of the drip pan 10 is turned upwardly, as at 13, and is provided with a plurality of seats 14 upon which rests a substantially annular air manifold 15. An appropriate inlet pipe 16 is provided for the manifold, said pipe extending to any convenient location, outside of the furnace if desired, and being preferably provided with a muffler 17 for deadening sound which might otherwise pass therethrough from the nozzle 2. It may be noted that the manifold 15 is spaced at a distance from the other dependent side wall of the hood 6 affording adequate space therebetween for the flames to issue, and at such time the flames will play upon the manifold heating the air within chamber 7. A discharge pipe 18 connects the manifold 15 with the air opening 4 of the injection tube 5, and the air opening 4 of the injection tube passes downward outside of the tube 5 onto a sloping annular shelf 8 where it burns. A fitting 1, thereby supplying pre-heated air to the chamber of said fitting.

The seats 14 are preferably, as shown, in the form of vanes integral with the drip pan and inclined with respect to radial lines in the same circumferential direction as the 5 vanes 11, see Figure 3, so that as the air enters at both opposite edges of the drip pan it is given a whirling action in one and the same circumferential direction.

A coil of pipe 19 is arranged in proximity 10 to the hood 6, the convolutions of said coil preferably having successively greater diameters so the coil will flare outwardly upward and be in the path of the flames which are thus caused to issue between said coil and 15 the air manifold. A supply pipe 20 is shown connecting with the bottom convolution of said coil 19, this supply pipe leading from a suitable source of water supply such as a city water main (not shown), and the upper 0 convolution of coil 19 is joined by a pipe 21 and a needle valve 22 to the steam injecting nozzle 2. Said needle valve preferably has a stem 222 which passes outwardly through a suitable sleeve 23 and packing 24 to the 25 exterior of the furnace where it may be manually controlled by the operator through any suitable agency, such as a handle 25. Heat from the flame will cause the water in the coil to turn to steam and this steam is fed 30 down through pipe 21 and needle valve 22 to the nozzle 2. It may be here noted that said nozzle is exteriorly screw-threaded and adjustable into or out of the injection chamber. This adjustment, however, is made in 35 setting up the apparatus and need not be changed thereafter. A lock nut 26 secures the nozzle in its adjusted position.

Similarly, the fuel supply nozzle 3 is screw-threaded and provided with a lock nut 27 for 40 obtaining a fixed adjustment of the nozzle. Fuel may be supplied to this nozzle from a suitable source, preferably at a steady or even pressure of any sort. As one way of securing such a feed, I have shown a gravity 45 feed through a pipe 28 and a float valve tank 29 having a float 30 and stop valve 31 which will act to maintain a constant level of fuel in said tank 29, which is preferably outside of the furnace at some convenient place and 50 fixedly supported at the proper level.

Note may be made of the fact that after the burner is once started in operation, it is regulated wholly by the single steam control needle valve 22. Also, the steam nozzle 2 is 55 in alignment with the burner tube 5 so the steam jet will pass directly up said tube and draw the fuel and heated air with it to the top of said tube into the mixing chamber. The fuel supply nozzle 3 is at an angle or 60 inclined to the line of discharge of the steam nozzle 2 and is shown adjusted longitudinally with its outlet at said line of discharge. However, it can be backed away or the steam 65 nozzle 2 can be backed away or advanced, as necessary to secure the desired action of steam

and fuel. It will be noted that the steam and fuel first combine and then by their passage into the tube 5 draw in such air as is needed from the injection chamber, to which it is supplied by the inlet pipe 4, though not under pressure or from a jet or nozzle. By my construction a proper adjustment in position of the fuel nozzle and steam nozzle, relative to each other, will result in an automatic induction of the proper amount of air after the steam jet has taken up the proper amount of fuel. The steam jet is the only one of the three supplies under pressure, and as has been stated, the entire feed is regulated by regulating the steam jet by means of the valve 22.

Preferably the hood 6 is provided with a plurality of interior vanes 32, herein shown as crescent shaped, said vanes resting upon the upper end of the tube 5 and hub 81, and said hood being held down in place by bolts 33 through said vanes into said hub. The injected gases strike the top of the hood and are deflected outwardly with a whirling motion caused by said vanes 32, thus causing the said gases to become thoroughly mixed before passing down to the shelf 8 for combustion.

In making installation of the burner in a furnace of ordinary make, the usual furnace grate is omitted or removed and preferably replaced by a plate 34 having an opening of appropriate size to substantially fit around the air manifold 15 and prevent an influx of cold air between said manifold and the wall 35 of the ash-pit of the furnace. Furthermore, the burner may be suitably supported in any desired way, and in the drawing I have shown a base or stand 36 adapted to rest upon the floor of the ash-pit and secured to a suitable part of the burner, such as to the discharge pipe 18 from the manifold.

Obviously detail changes and modifications may be made in the construction, operation and use of my improved oil burner, by those skilled in the art, without departing from the spirit and scope of the invention, and I do not wish to be understood as limiting myself herein except as set forth in the following claims when construed in the light of the prior art.

Having thus described the invention, what I claim is:

1. An oil burner comprising means for injecting ingredients to form a combustible mixture, means for mixing said ingredients, a sloping shelf on which to burn the mixture, a drip pan at the lower edge of said shelf, a manifold extending peripherally around said drip pan, and means for obtaining auxiliary supplies of air between the shelf and drip pan and between the drip pan and manifold.

2. An oil burner comprising a central hood, a shelf beneath said hood on which combus-

tion takes place, a steam coil around said hood, a manifold at the outer edge of said shelf, and means for mixing oil with steam from said steam pipe and air from said air manifold and conducting the mixture to said hood.

3. An oil burner comprising a central hood, a shelf beneath said hood on which combustion takes place, a steam coil around said hood, a manifold at the outer edge of said shelf, means for conducting an auxiliary supply of air to said shelf, and means for mixing oil with steam from said steam coil and air from said air manifold and conducting the mixture to said hood.

4. An oil burner comprising a central hood, a shelf beneath said hood on which combustion takes place, a steam coil around said hood, a manifold at the outer edge of said shelf, means for obtaining an auxiliary supply of air between said shelf and drip pan and between the drip pan and air manifold, and means for mixing oil with steam from said steam coil and air from said air manifold and conducting the mixture to said hood.

5. In an oil burner, the combination with a burner tube, of a hood mounted thereon and providing a downward extending annular passage around said burner tube, and an annular series of vanes centrally disposed at the interior of said hood and resting at their edges upon the end of the burner tube to support said hood so that the fuel mixture must pass from the said tube to said annular passage through said vanes.

6. In an oil burner, the combination with a central shelf and means for supplying fuel thereto for combustion, of an annular drip pan around said shelf, the adjacent edges of said shelf and drip pan providing an air gap, and vanes in said air gap disposed obliquely thereof and integral with said shelf and drip pan to connect the same.

7. In an oil burner, the combination with a central shelf and means for supplying fuel thereto for combustion, of an annular drip pan around said shelf, a manifold around said drip pan, said drip pan providing air gaps between its edges and said shelf and manifold, and vanes in said air gaps disposed obliquely thereof, the vanes between the shelf and drip pan being integral therewith to connect them and the vanes between the manifold and drip pan being integral with the latter and forming a seat for the former.

8. In an oil burner, the combination with a central shelf and means for supplying fuel thereto for combustion, of an annular drip pan around said shelf, a manifold around said drip pan, said drip pan providing air gaps between its edges and said shelf and manifold, and vanes in said air gaps disposed obliquely thereof, those in one gap being slanted in the same circumferential direction as those in the other gap so as to give

a whirling motion to the air entering oppositely through said gaps.

9. In an oil burner, the combination of an upright burner tube having a wide annular top, means for supplying a mixture of fuel gasses to the lower end of said tube, a hood upon said tube depending therearound to form an annular outlet and having at its center an annular series of interior vanes resting upon the top of the tube and forming with said top radial tubular passages leading to said outlet, and means below said outlet from which combustion takes place.

10. In an oil burner, the combination of an upright burner tube having a wide annular top, means for supplying a mixture of fuel gasses to the lower end of said tube, a hood upon said tube depending therearound with an inwardly converging wall forming at its lower end an annular outlet, said hood having at its center an annular series of interior vanes resting upon the top of the tube and forming with said top radial tubular passages leading to said outlet, and an annular outwardly extending shelf below said outlet from which combustion takes place.

11. In an oil burner, the combination of an upright burner tube, an annular shelf having a central upwardly extending tubular portion with a thickened top fitting upon the outside of the top of said burner tube flush therewith, means for supplying a mixture of fuel gasses to the lower end of said tube, and a hood upon the burner tube and tubular portion of the shelf depending therearound to form an annular outlet and having at its center an annular series of interior vanes resting upon the tops of said burner tube and tubular portion of the shelf and forming with said tops radial tubular passages leading to the space between said hood and tubular portion of the shelf, said hood terminating short of said shelf to discharge the fuel onto said shelf for combustion.

12. An oil burner having a central outwardly overhanging steam generator, an annular combustion shelf beneath said overhanging steam generator, central means for mixing steam, fuel and air and conducting the mixture to said shelf, an upwardly extending annular member outside said shelf to form a combustion chamber, and means for admitting air at the inner side of said member and outside said shelf.

13. An oil burner having a central outwardly overhanging steam generator, an annular combustion shelf beneath said overhanging steam generator, central means for mixing steam, fuel and air and conducting the mixture to said shelf, an upwardly extending annular member outside said shelf to form a combustion chamber, an annular passage for admitting air at the inner side of said member and outside said shelf, and vanes in said passage disposed obliquely thereof.

14. An oil burner having a central outwardly overhanging steam generator, an annular combustion shelf beneath said overhanging steam generator, central means for mixing steam, fuel and air and conducting the mixture to said shelf with a rotary motion, an upwardly extending annular member outside said shelf to form a combustion chamber, an annular passage for admitting air to the inner side of said member and outside said shelf, and vanes in said passage disposed obliquely thereof to give the air a rotary motion in the same direction as the fuel mixture.
